CIRCUIT INTERRUPTER

Filed April 26, 1927

UNITED STATES PATENT OFFICE.

RUDOLF GASPARIK, OF NEW YORK, N. Y.

CIRCUIT INTERRUPTER.

Application filed April 26, 1927. Serial No. 186,741.

This invention relates to improvements in automatic circuit interrupters, and it is the principal object of my invention to provide a socket for the reception of a lamp or plug with an interrupter for making and breaking the circuit periodically at certain predetermined intervals.

Another object of my invention is the provision of an automatic circuit interrupter of this type using thermally actuated means by the heat generated by the flowing current during the period of circuit conductivity and causing the separation of contacts, whereafter upon the cooling of said means the separated contacts will again be engaged and thus complete the circuit.

A further object of my invention is the provision of a circuit interrupter of simple and inexpensive construction, yet durable and extremely efficient in its operation.

A still further object of my invention is the provision of a compact circuit maker and breaker in shape of a button adapted for insertion into any of the conventional, customary sockets.

These and other objects and advantages of my invention will become more fully apparent as the description thereof proceeds, and will then be specifically defined in the appended claims.

In the accompanying drawing, forming a material part of this disclosure:

Fig. 1 shows partly in section, and partly broken away a conventional socket equipped with a circuit making and breaking device constructed according to my invention.

Fig. 2 is a top plan view of a fibre disc and a block of insulating material, and co-operating parts.

Fig. 3 is a top plan view of a fibre disc forming with the disc, Figure 2, a frame or housing for the thermally actuated device.

Fig. 4 is a section on line 4-4 of Figure 2.

Fig. 5 is a section on line 5-5 of Figure 3.

A conventional, one-piece socket 10 within a sleeve 11 of insulating material, has the customary reduced part 12 forming a shoulder against which rests a disc 13 of fibrous material of a suitable size and shape. A rectangular block 14 of insulating material is secured by means of the rivet or eyelet 15 to the disc 13, and a smaller disc 16 of fibrous material is secured to disc 13 by means of the screws 17.

A screw 18 is screwed into the center of disc 16 and the head of this screw rests in

the contact end of socket 10 making contact with the main circuit, and passes through the entire arrangement pressing the same against the shoulder of the reduced part 12 of the socket 10.

As illustrated in Figure 2, the block 14 has laterally secured thereto a thermostatic element 19 by means of a screw 20.

An angular metal piece 21 (Fig. 4) is attached by means of the screw 22 to the block 14 and a silver rivet or contact piece 23 is provided on the metal piece 21, while 24 designates an insulating body on the lamina 19 which also carries a silver rivet or contact piece 25 oppositely disposed to contact piece 23.

A coil 26 of resistance wire is wound about body 24, the insulated end or start of which is indicated at 27, and this coil is directly connected with the element 19, as indicated at 28.

The eyelet 15 passes through an opening 29 in block 14, while a connection 30 connects this eyelet 15 with the metal piece 21, and the openings in the disc 16 which receive the screw 17 are designated 31.

As illustrated in Figure 4, the metal eyelet 32 or the like is located in substantially the center of disc 16 and has an inner thread 33 for the reception of screw 18, while a connection 34 attached to the beginning 27 of the coil 26 rests upon the eyelet 32 to form a contact therewith.

The device operates as follows:

The current enters at the head of screw 18, passes through the eyelet 32 and a connection 34 into coil 26 and enters at 28 the thermostatic element 19, passes the two silver contact pieces 25 and 23 into the metal piece 21 and through connection 30 into eyelet 15. The current will heat the coil 26 and evidently also the element 19, so that the same will bend and thus interrupt the contact between 23 and 25 and thus open the circuit.

It will be clear that the thermostatic element will cool and unbend again and return into its original normal position in which contacts 23 and 25 are again engaged so that the above described steps will be repeated.

It is to be understood that I have described and shown as an example the preferred form of my device, but do not wish to be limited to the exact construction disclosed, and reserve my right to make such changes in the general arrangement and the construction of the minor details of my device as come

within the scope of the appended claims without departure from the gist and spirit of my invention.

Having thus described my invention, what I claim as new, and desire to secure by Letters Patent is:

1. In a thermostat circuit making and breaking device a pair of fiber discs, a block secured to one of said discs, a thermostatic element secured to said block, an insulating body on said element, an angular metal piece secured to said block, a contact piece on said thermostatic element and a contact piece on said metal piece oppositely disposed to said contact piece on said thermostatic element, a coil on said insulating body in series with the main line, said thermostatic element adapted to be heated by the current and to bend so as to interrupt the circuit by disengaging said contact pieces.

2. A circuit interrupter comprising a pair of fibre discs, means for connecting both discs, a block on one of said discs, an angular thermostatic element attached with one of its branches to one side of said block, a contact on said element, the other branch of said element transversely disposed to said discs, an angular metal piece attached to the opposite side of said block, a contact piece on said metal piece oppositely disposed to the contact piece on said thermostatic element, an eyelet in one of said discs, a screw in said eyelet in connection with the main circuit, said thermostatic element adapted to be heated and bend under the influence of the current to disengage said contact pieces to interrupt the circuit.

3. A circuit making and breaking device having the shape of a button and adapted to be inserted into a socket, comprising a pair of discs, means for connecting both discs spaced from each other, an insulating block on one of said discs oppositely disposed to the other of said discs, an angular thermostatic element secured at one of its branches to one side of the block, an insulating body on the other branch of said element, a coil on said body, transversely disposed to said discs, said coil connected to the thermostatic element and to the main

line in series therewith, an angular metal piece secured to the opposite side of said block, a contact on the lower branch of said metal piece opposite to said element, a contact piece on said thermostatic element oppositely disposed to said contact on said metal piece, an eyelet having an inner thread adapted to receive the contact of the main line and to allow a heating of said coil and thermostatic element and bending of the same to interrupt the engagement between said contacts and to engage the same upon the cooling of the thermostatic element upon the interruption of the circuit.

4. The combination with a socket of a circuit interrupter adapted to be introduced into said socket, said interrupter comprising a pair of superposed and spaced fibrous discs, an eyelet in the center of the upper disc, an eyelet having an inner thread in the center of the lower disc, an insulating block on the lower of said discs, screws for connecting both discs, an angular thermostatic element secured with one of its branches to the side of said block, its other branch extending transversely to said discs, an angular metal piece secured with one of its branches to the side of said block oppositely disposed to the fastening of said thermostatic element branch, a contact on its other branch, a contact on the transverse branch of said thermostatic element oppositely disposed to the contact on said metal piece, a connection between said metal piece and the eyelet of the upper disc, an insulating body on the transverse branch of said thermostatic element, a coil on said body connected to said thermostatic element and to the main circuit, a screw in contact with the main circuit adapted to be screwed into the eyelet of the lower disc, and for holding the parts together, said thermostatic element being heated by the current from said main circuit and bending to interrupt the engagement between both contacts and to unbend when cooling to reestablish said contact.

Signed at New York, in the county of New York and State of New York, this 25th day of April A. D. 1927.

RUDOLF GASPARIK.
